UNITED STATES PATENT OFFICE

SAMUEL BOORN, OF LOWELL, MASSACHUSETTS.

IMPROVEMENT IN CUSHIONS FOR SHUTTLE-BOXES.

Specification forming part of Letters Patent No. 35,808, dated July 8, 1862.

To all whom it may concern:

Be it known that I, SAMUEL BOORN, of Lowell, in the county of Middlesex and State of Massachusetts, have invented a new and useful Improvement in Looms; and I do hereby declare the same to be fully described in the following specification, and represented in the accompanying drawings, of which—

Figure 1 denotes a top view of a metallic case provided with my invention, the same being applied to a race-rod of a loom. Fig. 2 is a horizontal and longitudinal section of the same.

The nature of my invention consists in an improved cushion to be applied to a metallic case, which is to be placed upon each end of the race-rod A of a loom, in order to receive the blows of the picker or picker-staff, either in its extreme forward or rearward movements, and thereby prevent the injury usually arising to the picker or its staff when stopped by a hard unyielding material.

The object of my invention is threefold: first, to prevent the violent concussion and wear of the picker; second, to greatly diminish the noise incident to the usual action of the picker and picker-staff; and third, to preserve the cushion in its normal condition.

In carrying out my invention I employ one or more disks, *a*, or other proper-shaped pieces of leather, for the outer surface of the cushion or that part against which the picker or picker-staff is to strike. Next against such disk or disks I place a thick annulus, block, or disk, *b*, of caoutchouc or india-rubber, and next in rear of such rubber portion I dispose a thick layer, *c*, of curled horse-hair, in manner as seen in the drawings. These layers of leather, india-rubber, and curled hair I place within

a metallic case, *B*, and confine them together and in the said case by means of a band or strap, *d*, passing around them in manner as shown in Fig. 2. A cushion and its case, constructed as above set forth and as shown in the drawings, I apply to each end of the race-way and on the race-rod of the shuttle-box thereof, it being confined to the rod *A* by screws, or in any other suitable manner.

I have found by experience of more than a year that the combination of leather, india-rubber, and hair, arranged as above set forth, mutually protect each other against the violent shocks of the picker or picker-staff, while at the same time they preserve such picker or staff from injury. A cushion, if made entirely of leather, soon becomes indurated and loses its elasticity. One of vulcanized rubber is liable soon to become softened or injured by the oil on the picker-rod, and besides, when inclosed in a metallic socket, it is likely to soon become so driven and compacted therein as to have its elasticity seriously impaired, if not entirely destroyed. By placing in the rear of the caoutchouc block a mass of curled hair, and in front of it a cap or covering of leather, I have found by experience that the caoutchouc is preserved intact, or will not only maintain its elasticity, but will be protected from the softening and injurious effects of the oil.

I claim—

My improved cushion, as made of a combination of leather, india-rubber, and curled hair, arranged within a metallic case, *B*, in manner and for the purpose set forth.

SAMUEL BOORN.
